UNITED STATES PATENT OFFICE

JOHN GRANT, OF LOS ANGELES, CALIFORNIA

REAMER

Application filed April 16, 1929. Serial No. 355,624.

This invention has relation to expanding reamers and, although not limited particularly to the specified type of work, has been designed, in its more specific details, for the reaming of wells. Further, although the specific design at present embodying the invention is for the purpose of taking a light reaming cut, without having sufficient expansion to perform the operation commonly known as under-reaming, the invention itself, its mechanism and mode of operation, is not necessarily limited, although it may be peculiarly adaptable, to that form of expanding reamer which has only a slight expansion and is therefore particularly useful for reaming rather than for underreaming.

Thus, as a general object, there is the provision of a simple, sturdy and effective form of expandable reamer; the more particular object is to provide an expandable reamer that is particularly, but not limitedly, adaptable to reaming with a light cut—a simple, strong and effective reamer which need only expand by a comparatively slight amount. The invention involves, so far as I am aware, an entirely new type of expanding and contracting movement of the reaming cutters. The nature of this expanding and contracting movement will be better understood from a consideration of the following expanded typical embodiment than from a general preliminary description; and I therefore proceed immediately to an explanation of such a typical embodiment, with the aid of the accompanying drawings in which

Figure 1 is a side elevation with parts shown in section, showing the reamer in its contracted condition.

Fig. 2 is a side elevation showing the reamer in its expanded condition.

Figs. 3, 4 and 5 are enlarged cross sections respectively on lines 3—3, 4—4 and 5—5 of Figure 1.

Figs. 6, 7 and 8 are enlarged cross sections respectively on lines 6—6, 7—7 and 8—8 of Figure 2.

Fig. 9 is a diagram illustrative of the expanding and contracting movement of the reaming cutters and

Fig. 10 is a cross section on line 10—10 of Figure 1.

In the drawings a reamer body 10 of suitable cross sectional design is illustrated, the body 10 having at its upper end a connected sub 11 which may, as far as operation and functions are concerned, be regarded as part of the body and is only made detachable for facility of assembly and disassembly. The sub and body have the usual watercourse 12 extending longitudinally through them to supply circulating fluid to the bit 13 attached as usual to the lower end of the body.

The reamer here illustrated has three cutters or cutter assemblies, although it is practicable to use two or any larger number. Illustrating the reamer thus with three cutters or cutter assemblies, the main portion of the body 10 is shown as being somewhat triangular in cross section so as to provide spaces or pockets, within the peripheral circle of the reamer body, in which the cutters are located. Three faces of the central portion of the body are shown as being somewhat recessed as at 15 to accommodate the roller cutters; but the precise configuration of body, or of its faces adjacent the cutters, is of no great importance so far as the invention is concerned.

Neither is the particular character of the cutters of any important bearing upon the invention. As will be seen from the consideration hereinafter discussed, it is only necessary that the cutters extend in a direction generally longitudinal of the body; their actual cutting members or edges to be formed as desired. For convenience of illustration and simplicity of description I have here shown the cutters as including roller cutting elements 20 mounted in pairs on the cutter spindles 21 and rotating on those spindles as axes. The spindles, in the present specific illustration, form the rotational bearings for the roller cutters; but, so far as the present invention is concerned, these spindles need only to be considered as the longitudinally extending members of the cutters or cutter assemblies, of whatever nature the cutter or assembly may be.

The general principle of cutter movement

involved in this invention is one that causes two longitudinally spaced points—one of which is not at, or substantially at, the longitudinal end of the longitudinally extending cutter—to be moved, and the cutter tilted in a direction or in a plane generally circumferential of the reamer body, and thus causing an end of the cutter to be projected outwardly from the reamer body beyond the circumference of the body or the normal circumference of cutter projection. Just how two said spaced points are moved—by what kind of means they are guided and held—is more or less immaterial to the invention, except that such points be movable as is herein stated. Also whether or not one of such points is at or near an end of the cutter is, at least to some extent and in some respects, immaterial.

20 Thus, for purposes of illustration, I show the upper ends of the several cutter spindles 21 carried in bores 22 in a limitedly rotatable collar 23 mounted on the body between the upper end of body proper 10 and the lower end of stub 11. This rotatable collar 23 has three downwardly overhanging lugs 24 which overhang the previously described recessed faces 15 of the body. The relationship between these overhanging lugs and the body faces is perhaps best shown in Figures 3 and 6, and from an inspection and comparison of these two figures it will be seen how the collar 23 has only a limited rotation with respect to the body 10, limited by engagement of the inner lug faces 30 and 31 with the several faces 15 of the body. It will also be readily understood, from an inspection of Figures 3 and 6, how the upper ends of cutter spindles 21, although necessarily somewhat loosely mounted in bores 22 in order to accommodate the tilting action to be described, are movable with the rotating collar 23 in directions substantially circumferential of the body.

45 The rotating collar mount for the upper ends of the cutter spindles is one manner of causing substantially circumferential movement of certain points on the cutter spindles. Another manner of causing substantially circumferential movement is illustrated and shown as applied to points located about centrally of the spindle lengths. At these points the body is provided with lugs 35 which may conveniently be welded into place and thus form substantially integral parts of the body. Spindles 21 pass through vertical openings 36 through these lugs 35. Openings 36 are in the nature of slots whose lengths extend circumferentially in the body.

60 As the tilting movements of the cutters are comparatively small, the lengths of slots 36 are comparatively small; these slots being made by the drilling of two offset round holes on centers located substantially on the circumference of the body, and then after-

wards smoothing out the small amount of material necessary to be removed in order to make a short slot. These slots 36 being located, as they are, at about the mid-points of the cutters, are of a circumferential extent equal to about half the circumferential swing of the upper end of a cutter spindle. This last statement is not a necessary restriction upon the invention; the spacing of the two guide points on the cutter lengths, in proportion to the length of the cutter, and as well as the locations of those points with reference to the ends of the cutter, may be varied as will become apparent.

70 The lower ends of the cutter spindles 21 are illustrated as resting loosely in sockets or bores 37 in the lower part of body 10. The looseness in these bores allows the lower ends of the spindles a small amount of movement, which may be desirable.

75 The nature of the expanding and contracting movements will now be best understood with reference to Figure 9, considered in connection with the other figures. In Fig. 9 the movement is purposely exaggerated and is indicated diagrammatically. In this figure point A represents the position of the longitudinal axis of the cutter when contracted, as in Figure 1; the cutter axis then preferably extending parallel to axis B of the body. 80 The circle at 21a represents the then position of the cutter spindle and the circular arc C represents the arc or circumference along which the two upper controlled points of the cutter are allowed to move. Suppose now that the upper end U and the mid-point M of the cutter are allowed to move around the circumference C, the upper point U being allowed to move through twice the circumferential angle that is allowed mid-point M. 85 In the aspect in plan, as shown in the diagram, the cutter then takes the position UML, the letter L representing the lower end of the cutter or cutter spindle. Now, if the controlled point M is at the middle of the 90 cutter length and that point moves half as far as the upper point U, then, as is apparent from the diagram, the lower point L not only moves outwardly from its initial position A but also moves in the same direction circumferentially as the points U and M have moved; and the bore or socket 37 is of such size and placement that when the lower spindle end has reached the position shown at 95 21b, corresponding to the lower end position L, the lower end of the spindle will then bear against the wall of the socket in such a direction as indicated by the arrow D, which direction is not radially outward from the body, but is at least to some extent circumferential of the body. This is desirable because, with the body rotating in the direction indicated by the large arrow on Figure 9 and the various sectional views, and with the reaction thrust on the cutter having a 100

circumferential component directed oppositely to the rotation, it is desirable that the lower end of the cutter be backed up by a bearing that takes at least a part of the circumferential thrust. The exact direction of the thrust on the lower expanded end of the cutter varies with varying formations, the speed at which cutting is being done, etc.; but, in general, the thrust direction on the cutter is somewhere between a direction radial to the body and a direction circumferential of the body, for instance, somewhat as indicated by the directional arrow T. By making the bore 37 in the nature of a slot as is indicated in dotted lines S in Figure 9, still better support for the expanded lower end of the cutter is obtained; and this may be done in cases where the pressure on the cutter is heavy.

Further discussing Figure 9 it will immediately be seen that, on the supposition that point M is the cutter mid-point, a point M₁ may readily be selected on circumference C at which, if the movement of point M were limited thereto, the lower end point L of the cutter would then rest on the radial line R through the initial position point A; and the lower end of the cutter would not in that case have moved circumferentially of the body to reach its expanded position. Thus, still assuming that point M is the cutter mid-point, the point of movement M₁ (the limit of movement of the cutter point M) can be selected so as either to give the lower end L a movement circumferentially in the direction of thrust (opposite to the direction of the body rotation) or to give the lower end L no circumferential movement, or to give the lower end L a circumferential movement component in a direction opposite the thrust (that is, to make the point L move off to the left of the radial line R).

On the other hand supposing that the point M represents a fixed point to which the cutter point M always moves, then the ultimate position of lower point L depends upon the relative longitudinal position of the cutter point M. In the diagram I have supposed that the movement point M represents half the movement that the movement point U, for the upper end of the cutter, represents; and that the point M is in the middle of the cutter length. Suppose, however, that the lower length ML of the cutter is longer than the upper length UM. This condition would be represented in the diagram of Figure 9 merely by extending the line ML an appropriate distance. Accordingly, by making the lower length ML appropriately longer than the upper length UM, the point L can again be brought to the radial line R or can even be carried to the left of that radial line in Figure 9.

Thus, it will readily be seen that the line of movement, and the expanded position point,

of the lower end of the cutter depends upon two factors, first, the position of the control point M with relation to the other control point U and the free point L and, second, upon the relative amounts of controlled movement allowed the points U and M. Without going into complications of mathematical formula to express these relationships, it will readily be seen that, on the supposition that the points U and M move in similar circumferential movements of different lengths (which, however, are not necessary limitations on the invention) then, in order to obtain some substantial movement of the lower or free point L in the direction of thrust on the cutter, it is desirable that the movement ratio AM to MU be not less than substantially the ratio LM to MU; or the ratio of movement AM to the movement AU be not less than substantially the length LM to the length LU. And, although not necessarily, it is desirable that the lower or free point L, move for expansion in the direction of thrust, or at least not move against the thrust direction; because in the latter case the thrust will then have the effect of opposing the expansion.

The cutter, mounted and moved as explained, moves its lower or free point outwardly, because of the fact that the upper end of the cutter is moved around circumferentially under the influence of the drag thrust of the formation on the cutters themselves and also on the rotatable collar 23; and also because, in the preferred form at least, the lower or free end of the cutter also moves circumferentially in the direction of the drag thrust. Although the drag thrust on the upper parts of the cutter, represented by the points U and M, may be comparatively light because those points are not radially expanded, the fact that those points move circumferentially further than does the lower or free point L gives the thrust at those points a leverage advantage over the thrust at the free point L and thus causes the latter point to be forced outwardly.

A few other considerations remain to be noted. As will readily be understood from a consideration of Figure 9, it is not necessary that the movements of the two controlled points U and M, be exactly circumferential or exactly like each other. For instance, if the upper controlled point U has moved from A to a position radially inside the point marked U in Figure 9, the free point L will project further; if to a point radially outside the point marked U, the free point L will not project so far. Conversely, with the point M located inside (toward the central axis B) of the point marked M in Figure 9, or be located outside that point marked M, the free point L will then be closer to the point A (have less expansion) or to

cated further from the point A (have more expansion).

Thus, within limits that will be readily understood, the movements of the two points U and M need not be exactly circumferential or exactly like each other.

The second remaining feature is this: that the point U need not be at or substantially at an end of the cutter. It is only necessary, as hereinbefore indicated, that the two controlled movement points U and M be spaced from each other, and that one, at least, of them, be not at the end of the cutter. Accordingly, as indicated by the dotted line extension U—U₁ in Figure 9 the cutter may extend longitudinally beyond the point U; and the free end U₁ then becomes an expanding end which will expand just like the free end L.

Throughout this description I have referred to the free end L as being the lower end of the cutter. It will be apparent, however, that the arrangement may be reversed, if desired, making the free end L the upper cutter end.

I claim:

1. In an expanding reamer, the combination of a body rotatable about a longitudinal axis, a cutter normally extending substantially longitudinally of the body, and means for guiding and limiting two longitudinally spaced points of the cutter in limited movements having a direction circumferential of the body, at least one of said guided spaced points being longitudinally spaced from an end of the cutter and one of the guided and limited movements being of lesser extent than the other.

2. In an expanding reamer, the combination of a body rotatable about a longitudinal axis, a cutter normally extending substantially longitudinally of the body, and means for guiding and limiting two longitudinally spaced points of the cutter in limited movements substantially circumferential of the body, at least one of said guided spaced points being longitudinally spaced from an end of the cutter and one of the guided and limited movements being of lesser extent than the other.

3. In an expanding reamer, the combination of a body rotatable about a longitudinal axis, a cutter normally extending substantially longitudinally of the body, and means for guiding and limiting two longitudinally spaced points of the cutter in limited movements having a direction circumferential of the body, one of the guided and limited movements being of lesser extent than the other.

4. In an expanding reamer, the combination of a body rotatable about a longitudinal axis, a cutter normally extending substantially longitudinally of the body, and means for guiding and limiting two longitudinally spaced points of the cutter in limited movements substantially circumferential of the

body, one of the guided and limited movements being of lesser extent than the other.

5. In an expanding reamer, the combination of a body rotatable about a longitudinal axis, a cutter normally extending substantially longitudinally of the body, and means for guiding two longitudinally spaced points of the cutter in movements having a direction circumferential of the body, at least one of said guided spaced points being longitudinally spaced from an end of the cutter, the ratio of the two limited movements of the two said spaced points being substantially the same as the ratio of the distances of the respective points from said end of the cutter.

6. In an expanding reamer, the combination of a body rotatable about a longitudinal axis, a cutter normally extending substantially longitudinally of the body, and means for guiding two longitudinally spaced points of the cutter in movements substantially circumferential of the body, at least one of said guided spaced points being longitudinally spaced from an end of the cutter, the ratio of the two limited movements of the two said spaced points being substantially the same as the ratio of the distances of the respective points from said end of the cutter.

7. In an expanding reamer, the combination of a body rotatable about a longitudinal axis, a cutter normally extending substantially longitudinally of the body, and means for guiding and limiting two longitudinally spaced points of the cutter in limited movements having a direction circumferential of the body, at least one of said guided spaced points being longitudinally spaced from an end of the cutter, one of the guided and limited movements being of lesser extent than the other and a bearing surface on the body against which said cutter end bears in a direction non-radial to the center of the body.

8. In an expanding reamer, the combination of a body rotatable about a longitudinal axis, a cutter normally extending substantially longitudinally of the body, and means for guiding two longitudinally spaced points of the cutter in movements substantially circumferential of the body, at least one of said guided spaced points being longitudinally spaced from an end of the cutter, the ratio of the two limited movements of the two said spaced points being substantially the same as the ratio of the distances of the respective points from said end of the cutter, and a bearing surface on the body against which said cutter end bears in a direction non-radial to the center of the body.

9. In an expandable reamer, the combination of a body rotatable about a longitudinal axis, a cutter extending substantially longitudinally of the body, guiding and limiting means on the body and engaging the cutter at a point longitudinally spaced from one cutter end and guiding that engaged point of

the cutter in a movement directed circumferentially of the body, and another guiding and limiting means on the body engaging the cutter at a point longitudinally spaced from the first guiding means and guiding its engaged point in a direction circumferential of the body, one of said guided and limited points being limited by its said means to movement of lesser extent than that of the other said point.

10. In an expandible reamer, the combination of a body rotatable about a longitudinal axis, a cutter extending substantially longitudinally of the body, guiding means on the body and engaging the cutter at a point longitudinally spaced from one cutter end and guiding that engaged point at the cutter in a movement directed circumferentially of the body, and another guiding means on the body engaging the cutter at a point near an end of the cutter and guiding its engaged point in a direction circumferential of the body, the first mentioned point being limited by its said means to movement of lesser extent than that of the second mentioned point.

11. In an expandible reamer, the combination of a body adapted for rotation about a longitudinal axis, a collar rotatable on and with reference to the body and having means for holding one end of a longitudinally extending cutter, a lug on the body longitudinally spaced from the rotating collar and having a closed-ended circumferentially extending slot through which the medial portion of said cutter may extend, and said longitudinally extending cutter engaging said collar and said lug slot and extending longitudinally beyond said slotted lug.

12. In an expandible reamer, the combination of a body adapted for rotation about a longitudinal axis, a rotating collar on the body and having means for holding one end of a longitudinally extending cutter, a lug on the body longitudinally spaced from the rotating collar and having a circumferentially extending slot through which the medial portion of said cutter may extend, and said longitudinally extending cutter engaging said collar and said lug slot and extending longitudinally beyond said slotted lug, the rotational movement of said collar being limited with relation to the body and the circumferential length of the lug slot being less than the rotational freedom of said collar.

13. In an expandible reamer, the combination of a body adapted for rotation about a longitudinal axis, a rotating collar on the body and having means for holding one end of a longitudinally extending cutter, a lug on the body longitudinally spaced from the rotating collar and having a circumferentially extending slot through which the medial portion of said cutter may extend, and said longitudinally extending cutter engaging said collar and said lug slot and extending longitudi-

nally beyond said slotted lug, the rotational movement of said collar being limited with relation to the body and the circumferential length of the lug slot being less than the rotational freedom of said collar, and the ratio of circumferential movement of the cutter in the lug slot to the rotational movement of the end of the cutter in the rotating collar being substantially not less than the ratio of the length distances of the lug engaged point and the collar engaged point, respectively, from the projecting end of the cutter.

14. In an expansive reamer, the combination of a body adapted for rotation about a longitudinal axis, a medial portion of the body being recessed for reception of cutters, the body at one end of its recessed portion having cutter-receiving sockets, cutters having each one end held in said cutter-receiving sockets and extending therefrom substantially longitudinally of the body, a limitedly rotatable collar mounted around the body at the other end of the body recessed portion, said collar having sockets receiving and holding the other ends of the cutters, and means on the body located at a medial part of the body recessed portion and engaging the cutters at points medial in their lengths to limit the circumferential movements of the cutters at those points.

15. In an expansive reamer, the combination of a body adapted for rotation about a longitudinal axis, a medial portion of the body being recessed for reception of cutters, the body at one end of its recessed portion having cutter-receiving sockets, cutters having each one end held in said cutter-receiving sockets and extending therefrom substantially longitudinally of the body, a limitedly rotatable collar mounted around the body at the other end of the body recessed portion, said collar having sockets receiving and holding the other ends of the cutters, and slotted lugs on the body rotated at a medial part of the body recessed portion, said lugs having circumferentially extending slots through which medial portions of the cutters pass and by which slots the cutters are guided at such medial points in the movements directed circumferentially of the body and limited in such movements to less than the circumferential movements of the ends of the cutters which are held in said limitedly rotatable collar.

In witness that I claim the foregoing I have hereunto subscribed my name this 30th day of March, 1929.

JOHN GRANT.
